CLAIM

The ornamental design for a computer, as shown and described.

DESCRIPTION

FIG. 1 is a front elevational view of a computer showing our new design;

FIG. 2 is a rear elevational view thereof;

FIG. 3 is a top plan view thereof;

FIG. 4 is a bottom plan view thereof;

FIG. 5 is a right-side elevational view thereof;

FIG. 6 is a left-side elevational view thereof;

FIG. 7 is a front, top and left-side perspective view thereof; and,

FIG. 8 is a rear, bottom and left-side perspective view thereof.

1 Claim, 8 Drawing Sheets
